UNITED STATES PATENT OFFICE

SIDNEY G. JOHNSON, OF RAHWAY, NEW JERSEY, ASSIGNOR TO GENERAL RAILWAY SIGNAL COMPANY, OF ROCHESTER, NEW YORK

SAFETY DEVICE FOR POWER OPERATED SWITCHES

Application filed May 20, 1929. Serial No. 364,464.

This invention relates to power operated switches for railroads, and more particularly to a safety device for protecting train movement over such switches which are out of order.

In practical operation of railroads, it sometimes happens that trains must be run over power operated switches which for some reason are out of order, or not operating properly in some respect. Various things may happen to prevent the proper operation of a switch machine in throwing a switch, or the operation of the regular signals controlling train movement over the switch. Under such conditions, it is the practice to allow trains to move over a switch under hand signals, after taking suitable precaution to assure that the train may safely pass over the switch, the switch being cranked over by hand, if necessary. Since train operation under such conditions depends upon the human element, it sometimes happens that the switch is not properly spiked, in accordance with the operating rules, or due precautions are not taken to be sure that the switch can not be improperly operated by power. The maintainer or someone of the train crew may believe the switch is safe, and give a hand signal to the engineer or motorman to proceed, when through carelessness or oversight, the switch is not in fact safe; and serious accidents have occasionally resulted from such failure of the human element.

With these and other considerations in mind, it is proposed in accordance with the present invention to provide a simple and dependable device for positively locking the switch points and at the same time displaying an indication which the engineers of trains may rely upon as showing that they may safely run over the switch.

Various other characteristic features and advantages of the invention will be in part apparent and in part pointed out as the description progresses.

In the accompanying drawings, Fig. 1 shows a typical layout of a power operated switch, and illustrates the way in which the locking device of this invention is applied; Fig. 2 is a fragmentary enlarged plan view

of the locking device and associated parts; Fig. 3 is a section through the locking device; and Fig. 4 shows a form of the locking device and target preferably employed.

Referring to Fig. 1, an electrically operated switch machine SM, of the type shown, for example, in the patent to Winthrop K. Howe, No. 1,288,897, dated December 24, 1918, is connected to the switch points 1 by the usual throw rod 2 and lock rod 3.

The locking device of the invention, in the specific form shown, comprises a plate 4 bolted to the tie rod 5, to which the throw rod 2 of the switch machine is connected. This plate 4 is suitably insulated, in accordance with recognized practice, so as to permit the application of the usual track circuits. In the plate 4 are two spaced holes 4^a and 4^b, spaced apart in accordance with the throw of the switch points. A bracket 6 is firmly fastened to one of the ties 7, adjacent tie rod 5, by lag screws or the like; and this bracket has upper and lower portions above and below the plate 4, as shown in Fig. 3. In this bracket 6 there is a hole, preferably oval or some other non-circular shape, which is aligned with one of the holes 4^a and 4^b in the plate 4 when the switch points are at a corresponding extreme position. The locking pin or bolt 8, provided with a target 9 at the upper end, can be inserted through these aligned holes, this pin being of such length that it must pass through the openings and securely lock the switch points, before the target is low enough to permit trains to pass.

If desired, a suitable circuit controller, shown diagrammatically in section in Fig. 3 may be attached to the tie 7, so that when the locking pin 8 is in place, an insulated button 10 presses down a spring contact member 11 out of engagement with a stationary contact 12. These contacts 11-12 may be included in a power supply or control circuit for the switch machine, so that no power can be applied to the switch machine while the locking pin is in place, or these contacts may be used to control the regular wayside signals, governing traffic over the switch, or some other signal indicating the manually locked condition of the switch.

With a switch equipped with the locking device of this invention, if the switch machine is out of order, and the regular way-side signals do not give indications permitting the train to pass over the switch, the engineer is supposed not to move his train over the switch unless he can see the target 9, which indicates that the locking bolt 8 is in place, and that the switch points are positively and directly locked. The locking bolt 8, and the openings in the bracket 6 through which it passes, are made oval, or of an equivalent shape, so that the target 9 will stand in position to be readily visible.

15 Various modifications and adaptations may be made in the specific structure shown and described, without departing from the invention.

What I claim is:—

20 1. In a device of the character described, 25 the combination with a switch and machine operating means therefor, of manually operable emergency means, wholly detachable, for directly fastening the switch points independently of said operating means, and 30 target means for indicating when said fastening means is effective.

25 2. A manual safety locking device for 30 power operated switches comprising, a member attached to the switch points, a fixed member, wholly removable emergency locking means for rigidly connecting said members if the switch points are in an extreme position, and a target carried by said locking 35 means for indicating when it is effective.

30 3. A safety lock for power operated 35 switches comprising, a bracket fixed to a tie, a member attached to the switch points, said member and bracket having holes therein aligned when the switch points are in one extreme position or the other, and a locking bolt with a target at its upper end adapted to pass through said holes, said bolt being formed to pass through said holes, only when 40 the target is positioned to face oncoming traffic.

35 4. In a safety locking device for power 40 operated switches comprising, a member attached to the switch points, a member fixed to a tie, said members having holes therein aligned when the switch points are in one extreme position or the other, a locking bolt adapted to enter said holes and having a target at its upper end, and a circuit controller operated by said bolt when it has passed entirely through said aligned holes.

50 5. A manual safety locking device for machine operated switches comprising, a member attached to the switch points, a fixed member, wholly removable emergency locking means comprising a rod for rigidly connecting said members if the switch points are in an extreme position, and means carried by said locking means for indicating when

it is effective and preventing proper clearance for a train if not so effective.

55 6. A safety lock for power operated switches comprising, a bracket fixed to a tie, a member attached to the switch points, said member and bracket having holes therein aligned when the switch points are in one extreme position or the other, and a locking bolt with a target at its upper end adapted to pass through said holes, said target projecting into the clearance diagram for a train unless the locking bolt is in locking position.

60 In testimony whereof I affix my signature.

SIDNEY G. JOHNSON.
